Attorneys

UNITED STATES PATENT OFFICE.

LOUIS A. WIELAND, OF PITTSBURGH, PENNSYLVANIA.

GATE.

Application filed July 16, 1923. Serial No. 651,873.

To all whom it may concern:

Be it known that I, LOUIS A. WIELAND, a citizen of the United States, and resident of Pittsburgh, in the county of Allegheny 5 and State of Pennsylvania, have invented a new and useful Improvement in Gates; and I do hereby declare the following to be a full, clear, and exact description thereof.

My invention relates to expandable gates 10 for use in elevators, in door-ways and for other purposes, and it has special reference to the type of gate which consists of upright bars connected by diagonal lattice bars which are attached to the uprights in such 15 a way that the uprights remain parallel when the gate is expanded and compressed.

One object of my invention is to provide an improved gate of the character indicated, which in its closed position shall occupy 20 less space than ordinary gates of the same type.

Another object of my invention is to provide a gate of the character indicated having means for attaching the lattice bars to 25 the upright bars in such a way that they cannot become detached from the uprights through accident or careless handling.

A further object of my invention is to provide a gate of the character indicated 30 having improved rigidity as compared with ordinary gates of the same type, the greater rigidity being obtained by a special arrangement of the lattice bars and their connection to the uprights.

In the accompanying drawing, Fig. 1 is a 35 side elevational view of a portion of a gate constructed in accordance with my invention, the gate being shown in its expanded position; Fig. 2 is a side elevational view of the same parts in their closed position; Fig. 3 is a horizontal sectional view on the line 3—3, Fig. 1, showing the manner in which the lattice bars are connected to the uprights; and Fig. 4 is an enlarged fragmentary side elevational view of one of the 40 joints between the lattice bars and the uprights.

In the drawing the numerals 2 indicate a 50 plurality of parallel upright bars each of which has a longitudinal slot 3 formed in one side, and communicating with a space 4 within the upright. The uprights 2 may be made in any desired cross-section, the only requirement being that an undercut 55 slot be provided having an enlarged area within the upright.

The upright bars 2 are joined by means of lattice bars 5 which are pivotally connected at their inner ends by means of rivets 6 and are arranged in two adjacent sets of 30 crossed lattice bars, forming a total thickness of four bars when the gate is viewed from above as in Fig. 3.

The upright bars 2 are alternatively connected to opposite sides of the lattice bars 5 by means of rivets 6^a which extend through the outer joints of the lattice bars and are permanently secured to the uprights 2. The uprights on one side are connected to one set of lattice bars, and the uprights on the other side are connected to the other set of lattice bars. Therefore, when the gate is closed as shown in Fig. 2, the space occupied by the gate is but little more than the combined widths of one-half of the upright 75 bars 2. This produces a saving in space of approximately one-half as compared with gates of ordinary construction in which all of the upright bars are on one side of the lattice bars, or in which the upright bars 80 are arranged opposite to each other on both sides of the lattice bars.

As best shown in Figs. 3 and 4, each of the sliding rivets 6 which connects the lattice bars to the upright bars extends within the cavity 4 of its upright bar and carries a rectangular lug 7 which is wider than the slot 3. The lugs 7 insure that the rivets 6 cannot be removed laterally through the slots 3, and they also increase the rigidity 90 of the gate because any attempt to distort the gate will be resisted by the lugs 7.

The gate constructed in the manner described above is very rigid, both edgewise and laterally. That is to say, the gate will 95 not sag when it is supported from one edge, and it will not bend if an attempt is made to fold it sidewise when it is open. This rigidity is produced by the two superposed sets of lattice bars, and also by the rectangular lugs 7.

While I have shown in the accompanying drawing a preferred embodiment of my invention, it will be understood that various 105 changes in the construction and arrangement of parts may be made without departing from the scope of my invention as set forth in the appended claims.

I claim as my invention:

1. An expandible gate comprising two sets 110 of lattice bars, each provided at its outer side with picket bars, and means for con-

2
necting said lattice bars in side by side relation to form a unitary structure, the sets of lattice bars being assembled in longitudinally off-set relation so that when expanded 5 the picket bars at one side of the structure will be off-set horizontally with respect to the picket bars at the other side thereof.

2. An expandible gate comprising two sets of pivotally connected lattice bars arranged 10 adjacent to each other and forming a combined thickness of four of said lattice bars, a plurality of parallel bars connected alternately to opposite sides of said lattice bars, and means for securing each of said 15 parallel bars to the adjacent set of lattice bars comprising a rivet extending through two of said lattice bars and into an undercut slot formed in said parallel bar, and a member carried by said rivet and received in 20 the enlarged interior portions of said slot.

3. An expandible gate comprising two adjacent sets of lattice bars, each of said sets being composed of lattice bars pivotally connected at their ends, a plurality of parallel bars connected alternately to opposite sides 25 of said lattice bars, the parallel bars on one side being connected to one set of said lattice bars and the parallel bars on the other side being connected to the other set of lattice bars, and means for securing each of 30 said parallel bars slidably to said lattice bars comprising a rivet extending through the joined ends of a pair of said lattice bars and also extending into an undercut slot formed in said parallel bar, and a rectangular member carried by said rivet and received in the undercut portion of said slot. 35

In testimony whereof I the said Louis A. WIELAND, have hereunto set my hand.

LOUIS A. WIELAND.
